UNITED STATES PATENT OFFICE.

PHILLIP H. COOK, OF MARICOPA, CALIFORNIA, ASSIGNOR OF ONE-THIRD TO WALTER V. HARRINGTON AND ONE-THIRD TO ARTHUR G. POTTER, BOTH OF OAKLAND, CALIFORNIA.

UPRIPPER.

Application filed May 4, 1921. Serial No. 466,793.

To all whom it may concern:

Be it known that I, PHILLIP H. Cook, a citizen of the United States, residing at Maricopa, in the county of Kern and State of California, have invented new and useful Improvements in Uprippers, of which the following is a specification.

The present invention relates in general to improvements in well tools and more particularly to an improved tool for vertically ripping or cutting well casing which has become "frozen" or stuck in the bore of the well, whereby the casing may be lifted out or removed more easily and expeditiously.

The primary object of the invention is to provide a tool which, after being lowered into the casing and when lifted or pulled upwardly, will longitudinally rip or cut thru the part of the casing which has 20 "frozen" in the well whereby said ripped portion will collapse and the casing may, therefore, be easily removed by being lifted out of the well, the cutting or ripping means being such that upon release of the "frozen" 25 or stuck portion, said cutting will cease and said cutting means engaging in the upper end of the slit or cut, provides for lifting the casing as the tool is hoisted or raised.

Another object of the invention is to provide a simply constructed, inexpensive, durable and reliable tool of the character described which tool may be operated with the ordinary well rigging.

The invention possesses other advantages 35 and features some of which, with the foregoing will be set forth at length in the following description where I shall outline in full that form of the invention which I have selected for illustration in the drawings accompanying and forming a part of the present specification. In said drawings I have shown one form of the construction of my invention, but it is to be understood that I do not limit myself to such form since the 45 invention as expressed in the claims may be embodied in a plurality of forms.

Referring to the drawings:

Figure 1 is a vertical sectional view of a section of well casing showing the tool in 50 side elevation and as it would appear while being lowered, the tool being broken and shown in part in section.

Figure 2 is a vertical sectional view of a section of well casing showing the tool in 55 side elevation and as it would appear while

being lifted, the lower portion of the casing being ripped.

Figure 3 is a cross sectional view taken on line 3—3 of Fig. 2.

Figure 4 is a fragmentary side elevation 60 of a modified form of tool showing two knives arranged to rip opposite sides of the casing.

Referring to the accompanying drawing in which there is shown one embodiment of 65 the invention, 4 designates the body of the tool having at its upper end a screw threaded stem 5 adapted to screw into a drill jar, not shown, of the ordinary well rigging, also not shown. The body is provided with a central 70 longitudinal slot or opening 6 and is tapered to a point 7 at its lower end. The slot or opening provides two opposite arms 8, each of which is substantially rectilinear in cross section. The outer side faces of these arms 75 are adapted to lie in close proximity to, if not in slight engagement with, the inside of the well casing 9, whereas the side edges of the arms will be considerably spaced from the inside wall of the casing. Thus it will 80 be seen that it is only necessary to provide for snug fitting of certain opposite portions of the body, or in other words, two sides thereof, with the inner wall of the casing.

By having the lower end of the body pointed 85 the tool will readily pass any obstructions encountered in the casing while being lowered, since in the practice with stem and jar attached, the tool will usually weigh over 90 3000 lbs. While the body as shown in the drawing is slotted and of a general rectilinear outline in cross section, it may be otherwise shaped if desired, provided it has sufficient body and weight to provide for accomplishing the ends to be later herein described, 95 and provided it may be readily attached to ordinary rigging and can be easily lowered. By having the body of the shape shown and described, the tool offers less resistance to sand or other obstructions while being lowered.

I mount upon the body of the tool, cutting or ripping means which, while the tool is lowered, will be held in inoperative position and when the tool is lifted or raised will 105 longitudinally rip or cut thru the wall of the casing as long as the casing offers enough resistance to the upwardly moving cutting means. I have found that when the part of the casing which has been "frozen" 110

or "stuck" in the well has been ripped, said portion will collapse, or in other words, be reduced in diameter due to collapsing, and eliminate the friction, and therefore, upon 5 further lifting of the tool, the cutting means will lift the string of casing bodily, rather than continue to rip. This is particularly true when the cutting means encounters the heavy, thick joint collar construction after 10 cutting thru or ripping the "frozen" part of the casing, altho the cutting means will, when the casing is tightly "frozen" or "stuck", readily cut thru said joint collars.

15 One form of cutting means I have found to be effective is shown in the accompanying drawing and comprises a heavy tool steel knife bar 10, tempered to have necessary hardness and strength. One end of the 20 knife is pivoted as at 11 in a recess or slot formed in one of the arms 8 of the body, the pivot extending horizontally as does the lower wall 13 of the slot or recess 12. The knife extends transversely across the slot or 25 opening 6 and its free end is movable up and down in a vertical slot 14 formed in the other arm 8 of the body. The sides of the knife snugly engage the sides of the slots 12 and 14. The lower wall of the slot 14 30 is in the same horizontal plane with the wall 13 whereby, when the knife is in operative position it will extend at right angles to the body 4. The free end of the knife is pointed, in any suitable manner as 35 at 16, so as to cut thru or rip the casing and collars and the knife is mounted so that the cutting point or end will project outwardly from the side of the body 4 while the tool is raised and lie within the upper 40 end of the slot 14 while the tool is being lowered. A retractile spring 17 is attached to the tool body and knife so as to normally hold the knife in down position. This spring will yield when the tool is lowered 45 and pull downward on the knife at the beginning of the up movement of the tool.

When the casing of a well becomes "frozen" or "stuck" and it is necessary to lift the casing out of the well, the tool is 50 attached to the rigging, not shown, and lowered into the casing until it reaches the point at which the "freezing" or "sticking" of the casing has taken place, or may be lowered to the bottom of the casing. While 55 the tool is being lowered the point 16 of the knife is engaged by the casing and the knife swings upward on its pivot against the action of the spring 17, so as to lie well within the slot 14 and in this way does not interfere with the lowering of the tool. When 60 the tool is lowered sufficiently far, the rigging is operated to raise the tool. Immediately upon lifting the tool the knife will, by reason of its weight and thru action 65 of the spring 17, swing downwardly at its

free end so as to bring the point in the position shown in Fig. 2. This causes the point to perforate the casing and upon a continued up pull, the knife will slit or rip the casing vertically as shown at X in Fig. 2. 70 The up pull on the knife tends to lift the casing but the "frozen" or "stuck" portion of the casing offers sufficient resistance to cause the knife to cut rather than lift. However, when the "frozen" part of the 75 casing has been gripped it will collapse, reduce in diameter, and become released from the bore. At this time as the casing offers so little resistance, comparatively, to the up pull of the knife, said knife will lift the 80 casing rather than cut or rip further. This arrangement is provided for by the formation of the cutting or ripping part of the knife, which part should be pointed or otherwise formed so as to rip, as described, but 85 should be blunt enough to avoid cutting after release of the "frozen" or "stuck" portion of the casing.

In Fig. 2 the lower part of the casing is shown as "frozen" or "stuck", whereas the 90 upper part is free.

Thus it will be seen that I have provided a simple, inexpensive and reliable tool by the use of which a great deal of time, labor and expense may be saved in pulling out 95 well casings.

In Fig. 4 I have shown a modified form of the tool. In this form, the body 18 of the tool has two knives 19 and 20, mounted as are the knives of the preferred form of the 100 invention, but so as to extend from opposite sides of the body. This form will longitudinally cut or rip the casing on opposite sides and otherwise will operate the same as the preferred form of the invention. 105

I claim:

1. A tool for ripping well casing which has become stuck or "frozen" in a well comprising a tool body adapted to be lowered and raised in a well casing and means on the 110 body including a pivoted member at all times in engagement with the casing and which immediately when the tool is raised from any point in the casing will, solely through frictional engagement with the 115 casing, be moved into and maintained in a position to cause the member to penetrate and rip the casing as the raising of the tool body is continued.

2. A tool for ripping well casing which 120 has become stuck or "frozen" in a well comprising a tool body adapted to be raised and lowered in a well casing and a knife pivoted on the body and arranged and constructed such that it is forced into and maintained in inoperative position solely by its engagement with the casing while the tool is being lowered and which, solely due to its frictional engagement with the casing, 125 immediately when the tool is raised from 130

any point within the casing, will move on its pivot so as to penetrate and rip the casing upon continuation of the lifting of the body.

- 5 3. A tool for ripping well casing which has become stuck or "frozen" in a well comprising a tool body having an opening therein and adapted to be lowered and raised in a well casing, a knife pivoted adjacent 10 to one end to the body within the opening and having its other end adapted to project outwardly from the opening, said knife being arranged and constructed so that when

the body is lowered it will extend in an upwardly inclined position from its pivoted 15 end and be held in inoperative position solely through its contact with the casing and whereby immediately when the body is raised from any point within the casing will solely through its frictional engagement 20 with the casing, move downwardly and outwardly through the opening so as to penetrate the casing and rip through the same as the raising of the tool body is continued.

PHILLIP H. COOK.
